LEWIS E. MORRISON, OF NEWARK, NEW JERSEY, ASSIGNOR TO HIMSELF AND
MATTHIAS PLUM, OF NEWARK, NEW JERSEY.

TRIPPING MECHANISM FOR PRINTING-MACHINES.

1,098,914.

Specification of Letters Patent.

Patented June 2, 1914.

Application filed February 27, 1908. Serial No. 418,021.

To all whom it may concern:

Be it known that I, LEWIS E. MORRISON, a citizen of the United States of America, and a resident of Newark, Essex county, New Jersey, have invented certain new and useful Improvements in Tripping Mechanism for Printing-Machines, of which the following is a specification.

This invention relates to a throw-off or tripping mechanism for platen presses. More particularly this tripping mechanism has been designed for use in combination with a sheet feeding device such as described and claimed by me in an application filed 15 February 17, 1908; Ser. No. 416,203. But it must be understood that this invention is applicable to other types of machines and in combination with other machine elements than the feed mechanism referred to above. 20 In this instance, my invention is shown applied to a platen press of a well-known type, usually called a job press. Presses of this type are provided with a mechanical tripping mechanism which is normally operated 25 at will by means of a tripping lever pivoted on the one side of the machine so that when a sheet misses, the operator can trip the form member and prevent smutting of the platen. It will be clear that this 30 method of tripping the press possesses certain disadvantages; it is not automatic in its action, but the operator depends upon being near the tripping lever for operating the same; further, the operator must keep 35 his attention focused on the operation of the machine in order to trip it when necessary, and even when the operator is attentive, he cannot always trip the press in time.

This invention provides for an automatic tripping mechanism for operating the tripping lever on the press and thus trip the form. No changes in the construction of the press or its tripping mechanism are necessary, but only such parts are added as will 5 accomplish the desired result. By the use of this invention the operator can direct his whole attention to the feed—if the machine is hand fed,—or if the machine is automatic throughout its operation, the operator can attend to more than one press and generally superintend the operation without being confined to one machine.

The invention provides an electric circuit which is normally broken, but which is closed when a sheet misses, and the closing of the circuit is caused to energize an elec-

tro magnet, which in turn actuates certain mechanical elements for throwing the tripping lever into "tripped" position.

It is, of course, immaterial just how the 60 various parts are constructed and placed on the machine, but the distinguishing feature of this invention is, that elements or parts already on the press contribute to actuate this tripping device.

To this end the invention comprises such elements and features of construction as will hereinafter appear in the detailed description while reference is had to the accompanying drawings, in which—

Figure 1 is a side elevation of a platen press having a movable platen and equipped with a tripping mechanism embodying my invention; Fig. 2 is a perspective view of the feeding device and parts of the tripping mechanism. Fig. 3 is a detail side view of the tripping lever with parts of the tripping mechanism; Figs. 4 and 5 are plan and front views respectively of Fig. 3, and Fig. 6 is a diagram of the electrical connections. 70

Referring now to Fig. 1 the reference numeral 1 indicates the frame of the machine having the platen 2 and the form member 3, which latter is shown tripped. 4 is the main shaft carrying a pinion 5 which drives the gear 6 on shaft 7. The gear 6 is on the one side of the machine and on the opposite side, on shaft 7, is a crank disk 8. The form is oscillated by means of two connecting rods 9 pivoted at 10 to the said gear 75 and crank disk respectively. 11 is the tripping lever pivoted at 12 and connected at 13 to a link 14 which is pivoted at 15 to a lever 16 fast on the rockshaft 18. Inside the frame the shaft 18 carries a lever 19 on 80 which is fixed a pin 20. This pin travels in a slot 21 in the bell crank 22 on shaft 23. A link 24 connects the bell crank with a lever 27 on the shaft 25 which carries the form. This latter shaft is mounted eccentrically in 85 the form carrying member 26 as usual. This above described mechanism is found 90 on presses of this type and works as follows:

When the lever 11 is thrown into the position shown in full lines, the shaft 18 is rocked rearwardly or to the left as viewed in Fig. 1 and the pin 20 traveling in the groove or slot 21 in the bell crank rotates the latter far enough to let the link 24 push 105 the lever 27 upwardly and turn the shaft 25 110 in its bushings around the pivot 28 and

move the form a slight distance away from the platen, when the parts are in the position shown; or in other words by throwing the lever 11 forwardly or to the right as viewed in Fig. 1 the form is tripped.

Referring now to Fig. 2, the reference numerals 30, 30 indicate two brackets which may be fastened to the frame by any suitable means. Between and carried by the 10 said brackets is the feeding device proper. 31 indicates a shaft journaled in the brackets and on which are hinged the arms 32, 32 carrying a second shaft 33. Tapes 34 pass over these two shafts, and are driven from 15 gear 6 through the gears 35, 36, 37 and 38, which latter is fast on shaft 31. The paper is in this instance supposed to be placed by hand upon the tapes 34 which in turn convey the sheet to the platen. During its 20 passage over the tapes, the sheet is side registered by the guides 39, 39 and is moved toward the stops 40, 40 carried by rockshaft 41. At the proper time the sheet is permitted to pass under the stops and drop on 25 the platen, and this is accomplished by rocking the shaft 41 upwardly, thus lifting the stops. The shaft 41 is rocked through the 30 instrumentality of the lever 42, link 43, bell crank 44, link 45 pivoted to lever 46 carrying cam roll 47, which latter coacts with the usual platen locking cam 48 on shaft 7. A 35 spring 49 keeps the stops 40 normally on the shaft 33. Two levers 50, 50 are pivoted at 51 on the brackets 30 and carry each a roll 52 coacting with cams 53, 53 carried by the arms 32. On the platen are mounted two rollers 54, 54 on which the levers 50 rest. Thus it will be clear that as the platen moves, the feed is oscillated around the 40 shaft 31 through the instrumentality of the rollers 54, levers 50, rollers 52 and cams 53, and in this manner the feed is always in the proper position with relation to the platen and when the latter moves down into printing 45 position the feed is lifted up out of the way by reason of the rollers 54 on the platen. The position of the platen locking cam 48 is not changed any by using this feed, but the various connections between 50 the cam and the stops are so proportioned as to raise the stops at the proper time—when the parts are in the position shown in Fig. 2. Various other details could be mentioned about this feeding mechanism, but 55 as I do not claim the construction thereof in this application, the above description will be sufficient to understand the main operation thereof and its relation to the tripping mechanism, which I will now describe.

60 Loosely pivoted on the shaft 41 are two arms 60, 60 which carry a rod or bar 61 on which is mounted fast a lug carrying a lip 62 of brass which forms one terminal in the electrical circuit as seen in Fig. 6. Directly below this lip is the second fixed ter-

70 minal in the shape of a brass plate 63 carried by a bar 64 and of course insulated therefrom. The rod 61 is free to oscillate in the arms 60 and is operated by the lever 65 connected by a flexible connection 66 to the one end of a bell crank 67 pivoted at 68, where also the lever 46 is pivoted; the other arm of the bell crank 67 carries a cam roll 69 coacting with the platen locking cam 48.

75 70 indicates the source of electrical supply and in the circuit is inserted an electromagnet 71 having an armature 72. The circuit is normally open during the operation of the machine, the movable contact 62 being held up as long as the cam roll 69 is on 80 the high part of the cam 48.

The parts are so timed, however, that when a sheet is fed by the tapes to the stops 40 and have reached the same, the cam roll 69 drops on the low part of the cam 48, 85 which causes the contact 62 to drop on the sheet and the circuit will remain open. Next the cam roll 47 drops on the low part of cam 48, thus raising the stops 40 to allow the sheet to pass on to the platen, and the 90 stops in turn raise the rod 61 and thereby the contact 62. The platen now passes down into printing position, but now both the rolls 47 and 69 are on the high part of the cam 48 and the stops are down and the 95 circuit broken. As the platen again returns to receive the next sheet, the cam roll 69 drops first on the low part of the cam 48, thus lowering the contact 62 on the sheet which is fed onto the stops, next the cam 100 roll 69 drops on the low part of the cam and the operation is repeated. If, however, the sheet should not be in place against the stops the circuit will be closed as contact 62 will then drop directly on contact 63 105 and the magnet 71 will be energized.

The armature 72 of the magnet is normally raised by a spring or otherwise, but when the magnet is energized the armature is attracted and held on to the cores until 110 the circuit is again broken, and I utilize the motion of the armature to cause the throw of the tripping lever. This will now be explained. See Figs. 1, 3, 4 and 5.

On the lever 11 is mounted a bracket 75 115 for supporting the various parts now to be described. The magnet 71 is carried thereby, and farther up is pivoted at 76 a latch 77 which is overbalanced by the long arm 78. A plate 79 is slidably mounted on pins 80 in the bracket 75 and is for the purpose of regulating the movement of the latch 77, as the latter cannot move beyond the limit of the slots 81 through which the pins project. Thus the latch is always held 120 upwardly by the weight of the arm 78 but is limited in its upward and downward motion by the plate 79. The bracket 75 forms a loop 82 and between said loop and the tripping lever 11 is mounted a roller 83. 125 130

The latch is connected to the armature of the magnet by a string or other light connection 84.

Pivoted at 85 on the connecting rod 9 is a lever 86 provided with a hook 87 and a roller 88. This lever rests on the roller 83 and passes between the tripping lever 11 and the loop 82 of the bracket 75. It will be seen from Fig. 1 that this lever 86 moves with the connecting rod 9 and constantly rests on the roller 83 sliding thereon and passing immediately under the latch 77.

When the sheets feed to the platen without missing, the tripping lever remains in the position shown in dotted lines, Fig. 1, and the lever 86 rides back and forth on the roller 83, but when a sheet misses and the electrical circuit is closed, the magnet 75 is energized and the armature is attracted and pulls down the latch 77. This happens when the press is wide open and the lever 86 is in the position shown in dotted lines in Fig. 1; on the following forward stroke of the form carrying member the lever 86 is also moved forward and the hook 87 engages the latch 77, which latter is down, and carries the tripping lever 11 with it and trips the form. On the return stroke the roller 88 engages the loop 82 and carries the tripping lever 11 back to its normal position, thus again untripping the form. If the next sheet misses, the same thing will of course happen again and the form will be tripped every time the magnet is energized, which happens every time a sheet misses. When it is desired to trip the press by hand, the roller 88 serves as a stop for the tripping lever 11.

The above describes the construction and operation of my improved tripping mechanism and it is seen that it is readily attached to the press and does not demand any changes in the construction thereof.

Broadly speaking the invention comprises the following three parts, the lever 86 to be attached to the connecting rod; the latch mechanism to be attached to the tripping lever 11 and the feeding mechanism or the equivalent therefor to be placed in front of the platen.

Various modifications may of course be made within the scope of the invention, thus it is immaterial whether the electrical circuit is normally open or normally closed, and the precise form shown need not be followed exactly, as I do not wish to be limited except as to the scope of the claims.

I claim,

1. In a platen press having a movable platen, a tripping mechanism, means for feeding sheets to the said platen, an electrical circuit, a fixed and a movable terminal in said circuit, the said two terminals being carried by the said sheet feeding means, a lever for controlling said tripping mecha-

nism, a sliding lever, a latch pivoted on said controlling lever and adapted to engage said sliding lever to cause the said controlling lever to be thrown into tripped position to actuate the said tripping mechanism.

2. In a platen press having an oscillating platen and an oscillating form member the combination of a sheet feeding device, an electrical circuit, normally open, means for closing said circuit when a sheet misses, a tripping mechanism, a lever controlling the same, an electro-magnet mounted upon said lever and adapted to be energized when the said circuit is closed, and means actuated by the said electro-magnet when the latter is energized, for causing the said lever to be moved into tripped position and actuate the said tripping mechanism without stopping the said press.

3. In a platen press having an oscillating form member and an oscillating platen the combination of an electrical circuit normally open, a magnet adapted to be energized by said circuit, a mechanical tripping mechanism, a controlling lever for the same, a latch mechanism mounted on said lever, a lever movable with the form member of said press, and means for causing the said latch mechanism to engage with the said movable lever when the said magnet is energized to cause the said controlling lever to be moved into tripped position and actuate said tripping mechanism.

4. In a platen press the combination of a mechanical tripping mechanism, a controlling lever therefor, a latch mechanism on said controlling lever and comprising a pivoted latch, means for limiting the movements of said latch, an electrical circuit normally open, an electro-magnet for causing a downward movement of the latch when the said circuit is closed, a form member, a lever movable therewith, a hook in said lever and means for closing the said circuit to energize the said electro-magnet whereby the said latch engages the said hook for moving the controlling lever into tripped position and actuate the said tripping mechanism.

5. The combination of a movable form carrying member, a mechanical tripping mechanism therefor, a lever for controlling said mechanism, a bar pivoted on said form carrying member and movable therewith, an electrically operated latch mechanism adapted to engage the said movable bar for moving the said controlling lever from its normal position and actuate the said mechanism to trip the form and means carried by the said bar adapted to engage the said controlling lever for returning the same to its normal position and untrip said form.

6. The combination of a movable platen, a cam for locking the same in printing position, a form member adapted to coact with

said platen, a tripping mechanism for said form member, an electrical circuit, a fixed and a movable terminal in said circuit, means for preventing the said two terminals from contacting during a given period, 5 means coacting with the said locking cam for causing the said two terminals to contact at a predetermined moment, a bar pivoted in said form member, a hook in said bar, an electro-magnet in said circuit, a latch operated by said magnet when the said two terminals contact, and adapted to engage the said hook for causing the said tripping mechanism to act.

15 7. The combination of a platen press having a movable platen, a movable form member adapted to coact therewith, a tripping mechanism for said form member, a hand lever for causing said tripping mechanism 20 to act at will, means for conveying a sheet to said platen, a locking cam for locking the latter in printing position, movable stops for arresting the movement of a sheet at a given point, an electrical circuit, a fixed terminal in said circuit and located below the plane in which the sheet moves, a movable terminal in said circuit supported above said plane, means coacting with the said platen locking cam for preventing the said 25 30 two terminals from contacting during a given period, and for causing the said movable terminals to drop when a sheet is abutting the said stops above the fixed terminal, a latch carried by the said hand lever, a bar pivoted on the said form member and normally out of engagement with the said latch, which latter is caused to engage the said bar by the contacting of the said two terminals for throwing the said hand lever into 35 40 tripped position to actuate the said tripping mechanism.

8. The combination with a movable form member, a tripping mechanism therefor, a hand lever for actuating said mechanism, a latch mechanism on said lever, a movable member slidably supported between the said lever and the said latch mechanism, an electrical circuit for causing the said latch mechanism to engage the said movable member to throw the hand lever into tripped position and actuate the said tripping mechanism, and a roller carried by said movable member and adapted to return the said hand lever to its untripped position.

55 9. The combination of a platen press having an oscillating platen, an oscillating form member, a mechanical tripping mechanism for preventing the said form member from coacting with the said platen, a manually 60 operated lever for actuating the said tripping mechanism, the said lever being normally at rest, a latch mechanism carried by and movable with the said lever and automatic means for operating the said latch 65 mechanism to cause the said lever to be

moved from its normal position and actuate the said tripping mechanism without stopping the said press.

10. In a printing machine having an oscillating platen and an oscillating form member the combination of an electrical circuit, two terminals in the said circuit in the path of the sheet, means for keeping the one of the said terminals away from the other one except when a sheet passes between them, 70 a tripping mechanism, a manually operated lever controlling the latter and normally at rest and means actuated by the closing of the said circuit when a sheet fails to pass between said terminals whereby the said lever is thrown to actuate the said tripping mechanism to trip the said form member without stopping the press.

11. In a platen press having an oscillating platen and an oscillating form member, a cam on the press for locking the said platen in printing position, a tripping mechanism, an electrical circuit for operating the same, a movable and a fixed terminal in the said circuit and normally open, and means coacting with the said platen locking cam for causing the said two terminals to contact and close said circuit to operate the said tripping mechanism.

12. The combination of a movable form member, a connecting rod for operating the same, a mechanical tripping mechanism connected to the said form member and normally at rest, a lever controlling the said tripping mechanism, said lever being normally stationary, a member interposed between the said form and the said lever and pivoted on the said connecting rod, and means for causing said lever to be engaged by the said member to actuate the said tripping mechanism.

13. The combination of a movable form member, a mechanical tripping mechanism, a hand lever controlling the latter and normally at rest, a member pivoted on the said form member and movable therewith and means for causing the said pivoted member to engage the said hand lever to trip and untrip the said form member.

14. The combination of a movable form member, an oscillating sheet conveying device, an electrical circuit, two contacts in the latter carried by the said sheet conveying device, means for oscillating one of the said contacts independently of the oscillation of the said device, a tripping mechanism and means operated by the closing of the said contacts to actuate the said tripping mechanism to trip and untrip the said form member.

15. In a platen press the combination of a sheet conveying device, a lower fixed member and an upper movable member carried by the said device, the said two members being normally out of contact, means for

causing the said upper member to fall by gravity upon the said lower member and devices actuated by the contacting of the said two members for tripping and automatically untripping the said press.

16. In a platen press the combination of sheet conveying means, a lower fixed and an upper movable member secured to the said means, the said two members being normally 10 out of contact, means for causing the said upper member to fall by gravity upon the said lower member and devices actuated by the contacting of the said two members for tripping and untripping the said press.

17. In a platen press the combination of sheet conveying means, mechanism for oscillating the same constantly, two members carried by the said conveying means, one of the said two members being movable with 20 relation to the other member and independently of the oscillations of the said means, the said two members being normally out of contact, means for causing the said movable

member to fall by gravity onto the said other member and devices actuated by the 25 contacting of the said two members for tripping and untripping the said press without stopping the oscillations of the said sheet conveying means.

18. In a printing machine the combination of an electrical circuit having two terminals, means for oscillating the same simultaneously, other means for operating one of the said two terminals independently of the said oscillating movement, a tripping 30 mechanism and means actuated by the closing of the said circuit through the said two terminals for actuating the said tripping mechanism for automatically tripping and untripping the said machine. 35

Signed at Newark, N. J. this 24th day of Feb 1908.
